UNITED STATES PATENT OFFICE.

WILLIAM J. ARNOLD, OF KANSAS CITY, KANSAS.

REFRIGERATING DEVICE FOR BOX-CARS.

SPECIFICATION forming part of Letters Patent No. 416,285, dated December 3, 1889.

Application filed February 19, 1889. Serial No. 300,411. (No model.)

To all whom it may concern:

Be it known that I, WILLIAM J. ARNOLD, of Kansas City, Wyandotte county, Kansas, have invented certain new and useful Improvements in Refrigerator-Cars, of which the following is a full, clear, and exact description, reference being had to the accompanying drawings, forming a part hereof.

This invention relates to improvements in refrigerator-cars; and it consists in a certain novel construction and arrangement of devices, as fully described hereinafter in connection with the accompanying drawings, and specifically pointed out in the claims.

15 In the drawings, Figure 1 is a sectional end elevation of a railroad-car embodying my invention. Fig. 2 is a part longitudinal section of the same. Fig. 3 is a detached perspective view of a cleat or strip interposed between 20 each ice tank or receptacle and the car or inclosure, and Fig. 4 is a similar view of a bracket, a number of which are used in supporting the ice tanks or receptacles.

In carrying out my invention I employ an 25 ice tank or receptacle B, or a number of the same, according to the requirements of the case, in the present instance four tanks or receptacles being provided in a car of ordinary size. The tank or receptacle B is or may be 30 rectangular or cylindrical or other shape in cross-section, but gradually flares or increases in size downward, thus being larger at the bottom than at the top, whereby it is obvious the ice placed therein will by gravity continuously settle toward and always rest upon the 35 bottom of the tank or receptacle as it reduces or lessens in bulk from melting. The advantage of this is that the salt pickle or brine in the bottom of the tank or receptacle will always be in contact with the ice and be kept 40 at a freezing-temperature, thus preventing the salt pickle from becoming warm, which would result in rising temperature. This latter is a disadvantage that often arises or happens 45 in the use of ice tanks or receptacles having a uniformity of cross-section, owing to the clogging or wedging together of the ice, which holds it away from the salt pickle or brine, resulting, as above intimated, in its becoming 50 warm and in rising temperature, the consequence of which is the contents of the car are injured. These tanks are supported

in position by means of brackets C C', bolted through their vertical portion at f f to the end of the car, and angle-irons or approximately L-shaped castings G, fastened or bolted to the sides of said tanks and resting upon said brackets. The brackets C C' are each of a proximate inverted-L shape, and have a short foot g, which is fastened to the 60 floor of the car, and they (the brackets) are preferably T-shaped in cross-section in their vertical portions, and have in their horizontal portions or arms at a suitable distance apart perforated or apertured flanges G'. Through 65 apertures in said flanges G' and apertures in the horizontal portions or arms of the angle-irons or castings G are inserted bolts fastening the same together.

The brackets C are relieved of a portion of 70 their strain by the diagonal brace-rods D, passed through the outer ends of their horizontal arms and nutted below the latter and extended up to and looped, as at b', upon pendent screw-hooks b, screwed into the upper edge of the car-body. The end brackets 75 C', however, have no brace-rods applied to them, none being needed there.

The tanks or receptacles B are isolated or separated from the car by scalloped or serially-notched bars or strips E, to permit of the circulation of air-currents behind said tanks or between the same and the car, the air passing through the notches aforesaid. The tanks are provided with downwardly-curved or dished bottoms, having their lowest point at the center in order to cause the sawdust, dirt, &c., to collect at that point, whereby it may be readily removed, and plugged openings h in the sides of the tanks 90 or receptacles B permit of the clearing of the same when desired. These tanks or receptacles are also provided with overflow-pipes H, discharging into pans F below, from which the water passes through the outlets d in the 95 bottom of the car.

The openings in the top or roof of the car, through which the tanks or receptacles are supplied with ice, may be provided with rounded or flat trap-doors a, which are preferably hinged at their inner edges to the roof of the car, and are engaged at their outer edges by suitable buttons K along the lower edge of the roof.

The tanks are preferably arranged in pairs, as shown in Fig. 1, with their adjacent walls b^2 b^2 connected by a rounded portion or projection b^3 . The outer or remote sides of each 5 pair of tanks are extended upward and flared outwardly to fit in the openings in the roof of the car, and caps or lids a' are fitted in the flared mouths of the tanks and bear at their centers on the rounded portions b^3 , which 10 connect the adjacent walls of the tanks, thereby separating or cutting off all communication between the tanks. It will be seen that this mode of connecting the tops of the tanks to the car causes a portion of the 15 weight of the former to be supported by the roof of the car, and also enables a perfectly air-tight joint to be effected between the walls of the tanks and the cap or lid. The caps or lids may be secured in place in any ordinary or preferred manner, and the under sides of the trap-doors a a are recessed, as at a^2 , to provide an air-space above said caps or lids, which acts as a non-conductor of heat. 20

The peculiar manner of supporting the 25 tanks by means of angle-irons G , attached to its side walls and resting on brackets, leaves the lower ends of the tanks freely suspended and out of contact with all wood-work and iron-work, thereby permitting the ready cleaning of the drip-pans of all impurities or sediment, and preventing the circulation of impure air which would arise in the presence of saturated wood-work. Such saturation is liable to occur from the dripping or overflow 30 water, thereby producing a sour and moldy atmosphere, the effect of which, it is obvious, is to injure the contents of the car. A further advantage of this peculiar manner of supporting the tanks in position is, that their 35 entire surfaces are exposed to the currents of air within the car, thereby increasing the effectiveness of the tanks, and producing a lower temperature with the same consumption of refrigerating material. 40

45 It will be understood that my tank or receptacle can be applied or used in storage-refrigerators in meat stores and elsewhere.

Having thus described my invention, what I claim, and desire to secure by Letters Patent, 50 is—

1. In a refrigerator - car, the tanks arranged in pairs, with their adjacent walls connected by an integral rounded portion or projection and having their outer walls flared outwardly to fit in flared openings in the roof of the car, and the caps or lids fitting in the flared mouths of the tanks and bearing at their centers on the intermediate rounded portion or projection between adjoining tanks, substantially as specified. 55

2. In a refrigerator-car, the combination, with the supporting-brackets C , attached to the sides of the car, the horizontal arms thereof having apertured flanges G' , of the tanks B , having hemispherical or semi-cylindrical bottoms and suspended between the brackets C by means of the angle-irons G on their sides, whereby the lower parts of the tanks are below the horizontal arms of the brackets and in front of their vertical arms, 70 giving ready access to the tank-bottom, substantially as described.

3. In a refrigerator-car, the combination, with the brackets C , provided with horizontal apertured arms and having horizontal feet g resting on the floor of the car, of the tanks arranged at their lower ends between the horizontal arms of the brackets and provided at their sides with angle-irons which rest on said horizontal arms and are bolted thereto, 75 substantially as specified.

4. In a refrigerator-car, the combination of brackets arranged at intervals and having parallel horizontal arms, the tanks arranged at their lower ends between said horizontal arms and provided above their lower ends with side projections bearing on the brackets, and the brace - rods arranged between the tanks, connected at their upper ends to the car and at their lower ends to the free ends 85 of the horizontal arms of the brackets, substantially as specified. 90

In testimony whereof I affix my signature in presence of two witnesses.

WILLIAM J. ARNOLD.
